WATER CLOSET FLUSH VALVE.

APPLICATION FILED DEC. 3, 1906.

2 SHEETS—SHEET 2

UNITED STATES PATENT OFFICE.

JOHN KELLY, OF CHICAGO, ILLINOIS.

WATER-CLOSET FLUSH-VALVE.

No. 843,949.

Specification of Letters Patent.

Patented Feb. 12, 1907.

Application filed December 3, 1906. Serial No. 346,178.

To all whom it may concern:

Be it known that I, JOHN KELLY, a citizen of the United States, residing at Chicago, in the county of Cook and State of Illinois, have invented a new and useful Improvement in Water-Closet Flush-Valves, of which the following is a specification.

My invention relates to an improvement in the class of automatically-operating water-closet flush-valves for controlling the supply of flushing-water to a tank, into which the charge thereof is admitted by depressing the closet-seat to move the valve to one position and from which the charge enters the bowl to flush it as the result of removing the pressure from the seat to permit the valve to assume its other position.

The object of my invention is to provide a novel construction of valve device in the class referred to which shall render it simple and relatively cheap to manufacture and durable and reliable in operation and which shall adapt the valve proper to be readily accessible for the purpose of withdrawing it from its casing for repacking and for replacing it into operative position therein.

Referring to the accompanying drawings, Figure 1 is a broken section taken at the line 1 on Fig. 4 and viewed in the direction of the arrow, showing my improved valve device interposed between a bowl to be flushed and a tank for receiving the charge of flushing-water, the valve proper being shown in its normal position; Fig. 2, a view showing the valve device in sectional elevation with the valve proper in the position to which it is raised by depressing the seat to admit a charge of flushing-water into the tank; Fig. 3, a broken section of the valve device, taken at the line 3 on Fig. 1 and viewed in the direction of the arrow; and Fig. 4 a broken plan view of the rear portion of a closet bowl and seat, showing in cross-section the stem of the valve device in position to be operated by the seat.

The valve-casing 5 is of general cylindrical shape and has extending laterally from it a hollow arm 6, divided longitudinally by a central partition 7 into passages 8 and 9, the arm terminating at its outer end in an upper turned internally-threaded nipple 10 and the passage 9 terminating at its outer end in a downwardly-extending internally-threaded nipple 11. As the construction is represented the partition function of the part 7 termi-

nates at the nipple 11, beyond which it is extended to form the base of the passage 8 and develops into the nipple 10. Adjacent to the inner ends of the passages 8 and 9 the casing 5 is shown to be enlarged at 12 and 13 to form chambers, between which at 14 fits one of the two valves, as and for the purpose hereinafter described. In the lower part of the casing is formed a partition 15, containing a central guide-opening 16, and beyond which extends the internally-threaded nipple 17 for receiving an annular screw-plug 18, between which and the partition packing 19 is interposed. The upper end of the casing is closed by a screw-cap 20, which is readily removable to permit access to the valves in the casing, hereinafter described, for facilitating their withdrawal therefrom, as for repacking them and their replacement. A nipple 21 extends laterally from the upper part of the casing 5 about a plurality of inlet-openings 22 therein and is adapted to be connected by a pipe 23 with a suitable source (not shown) of water under pressure. On a stem 24, which extends at its lower end beyond the casing, passing guidingly through the partition 15 and stuffing-box afforded by the plug 18, are provided at suitable distance apart the valve 25, surrounded by packing 26 to closely fit the interior of the casing at 14 above the chamber 13, and the upper valve 27, packed with an upwardly-extending cupped gasket 28, closely fitting the interior of the casing above the chamber 12. The cap 20 serves to confine the valve-stem in the casing.

In the operative position of the valve device it is coupled at the nipple 10 with a closed tank 29, at the nipple 21 with the supply-pipe 23, and at the nipple 11 with a thimble 30, leading upward through the flush-rim 31 of a water-closet bowl 32 of usual or any suitable variety. On the bowl is hinged, as represented or in any other suitable manner, the seat 33, from the center of the hinge of which a finger 34 projects backward underneath the lower end of the valve-stem 24 to rise with depression of the seat and affording the medium by its depression through which to raise the seat.

In Fig. 1 the movable parts of the valve device and the seat are shown in their normal relative positions, to which they are brought by the water-pressure, as hereinafter de-

scribed. By depressing the seat 33 the resultant rise of the stem 24 brings the valve 25 into the annular space at 14 to close communication between the passages 8 and 9 and the valve 27 above the inlet-openings 22 to open communication between the pipe 23 and the passage 8 to the flow of water from the supply into the tank 29. While the seat remains depressed this supply continues to fill the closed tank to the extent that its air-bound condition will permit. When the lowering pressure upon the seat is released, the water-pressure from the supply against the valve 27 and that exerted by the compressed air in the tank through the passage 8 against the valve 25 forces downward the valve-stem against the finger 34 to raise the seat into the position from which it is ready to be again depressed for effecting introduction into the tank of the next charge of flushing-water, and the charge in the tank 29 flows through the passage 8 past the valve 25 into the passage 9 and thence into the rim 31 to exert its flushing purpose, this flow continuing until the tank is emptied and in condition to receive the next charge as the result of depressing the seat to close communication between the two passages 8 and 9 and open communication between the passage 8 and the ports 22, as hereinbefore described.

What I claim as new, and desire to secure by Letters Patent, is—

1. In a flush-valve device of the character described, the combination of a casing provided between its ends with a laterally-extending hollow arm adapted to be coupled with a flush-tank and containing a partition dividing it into passages open to said casing, one of said passages being adapted to be coupled to the flush-rim of a closet-bowl, an inlet leading into the upper part of the casing and adapted to be connected with a source of water-supply, a valve-stem reciprocably confined in the casing to extend at one end beyond the same and provided with a valve normally closing communication between said inlet and one of said passages for supplying the tank, and with a second valve normally opening communication between said passages, for the purpose set forth.

2. In combination with a hinged water-closet seat having a finger extending from its hinge, a valve device of the character described, comprising a casing provided between its ends with a laterally-extending hollow arm adapted to be coupled with a flush-tank and containing a partition dividing it into passages open to said casing, one of said passages being adapted to be coupled to the flush-rim of a closet-bowl, an inlet leading into the upper part of the casing and adapted to be connected with a source of water-supply, and a valve-stem reciprocably confined in the casing to extend at one end

into engagement with said finger and provided with a valve normally closing communication between said inlet and the one of said passages for supplying the tank, and with a second valve closing communication between said passages when the valve-stem is raised from its normal position, for the purpose set forth.

3. In combination with a hinged water-closet seat having a finger extending from its hinge, a valve device of the character described, comprising a casing provided between its ends with a laterally-extending hollow arm adapted to be coupled with a flush-tank and containing a partition dividing it into passages open to said casing, one of said passages being adapted to be coupled to the flush-rim of a closet-bowl, an inlet leading into the upper part of the casing and adapted to be connected with a source of water-supply, a valve-stem reciprocably confined in the casing to extend at one end into engagement with said finger and provided with a valve normally closing communication between said inlet and the one of said passages for supplying the tank, and with a second valve closing communication between said passages when the valve-stem is raised from its normal position, and a cap removably fastened on and closing the upper end of the casing, for the purpose set forth.

4. In a flush-valve device of the character described, the combination of a casing provided between its ends with enlargements forming chambers and with a hollow arm extending laterally from it at said chambers and adapted to be coupled to a flush-tank, a partition in said arm dividing it into passages each opening into a different one of said chambers, and one of said passages being adapted to be coupled to the flush-rim of a closet-bowl, an inlet leading into the upper part of the casing above said chambers and adapted to be connected with a source of water-supply, and a valve-stem reciprocably confined in the casing to extend at one end beyond the same and provided with a valve normally closing communication between said inlet and the one of said passages for supplying the tank, and with a second valve interposed between said chambers when the valve-stem is raised from its normal position, for the purpose set forth.

5. In combination with a hinged water-closet seat having a finger extending from its hinge, a valve device of the character described, comprising a casing provided between its ends with enlargements forming chambers and with a hollow arm extending laterally from it at said chambers and adapted to be coupled to a flush-tank, a partition in said arm dividing it into passages each opening into a different one of said chambers, and one of said passages being adapted

to be coupled to the flush-rim of a closet-
bowl, an inlet leading into the casing above
said chambers and adapted to be connected
with a source of water-supply, and a valve-
5 stem reciprocably confined in the casing to
extend at one end into engagement with said
finger and provided with a valve working in
said upper chamber and with a second valve
working between said chambers, for the pur-
pose set forth.

JOHN KELLY.
